APPARATUS FOR TREATING STRANDS

Waldemar C. Ewaldson, Millington, and Heinz Kress, North Plainfield, N. J., assignors to Western Electric Company, Incorporated, New York, N. Y., a corporation of New York

Application September 3, 1938, Serial No. 228,352

2 Claims. (Cl. 91—31)

This invention relates to apparatus for treating strands and more particularly to apparatus for treating electrical conductor strands sheathed and treated with textile material, with a solution of cellulose acetate or the like in a solvent such as acetone or the like.

Textile covered wire has been treated in the past with many different liquid substances to coat or impregnate or to impregnate and coat the textile sheathing with various substances either in molten condition or dissolved in a volatile solvent. It is especially desirable in some cases to impregnate and coat the textile covered wire with cellulose acetate dissolved in acetone to improve both the electrical and mechanical characteristics of the insulating coating. Since the solvent in this case as well as in other similar cases is volatile, inflammable and may be injurious to health, it is necessary to provide an apparatus in which the coating process may be carried on continuously and rapidly in an enclosed space. It is desirable that the container or housing within which the coating is done shall be small in dimensions in order that all parts may be conveniently accessible for adjustment, cleaning, repair or the like.

An object of the present invention is to provide an apparatus for treating strands with liquid material which shall be reliable and safe in operation and shall be compactly constructed and arranged.

One embodiment of the invention may present an upright vertically extended housing of relatively small horizontal dimensions comprising a tank or reservoir in its bottom end to contain a supply of the liquid coating material, and having individual means respectively to contain a supply of strand to be treated, to guide the strand into and out of the bath of liquid, to guide the strand during the drying procedure in a tortuous path to and fro within the housing, to wipe off surplus coating material from the strand and compact the coating material on the strand, to propel or advance the strand through the apparatus, and to take up the coated strand at the end of the operation, together with auxiliary means to assist in threading the strand through the apparatus preparatory to operation, to prevent the formation of knots of coating material on the strand, and to prevent actuation of the apparatus unless all parts are in suitable operating relation to each other.

Other objects and features of the invention will appear from the following detailed description of one embodiment thereof taken in con-

nection with the accompanying drawing in which the same reference numerals are applied to identical parts in the several figures, and in which

Fig. 1 is a view in front elevation of an apparatus constructed in accordance with the invention and having parts of the housing broken away to show the interior mechanism;

Fig. 2 is an enlarged detached broken view of the lower end of the machine, also in front elevation;

Fig. 3 is a plan view of the showing of Fig. 2;

Fig. 4 is a view in end elevation of the convex roller die assembly in place.

Fig. 5 is a detached plan view of the convex wiper die roller assembly.

The apparatus herein disclosed as an embodiment of the invention is constructed with particular reference to the coating of textile covered wire with a solution of cellulose acetate in acetone. The apparatus comprises a vertically extended housing 20, conveniently of rectangular cross section and mounted upon any convenient and suitable base member 21 to be elevated somewhat above the floor. A supply reel diagrammatically illustrated at 22 contains a supply of strand 23 to be coated, and a take-up reel 24 similarly located is used to take up the coated strand emerging from the apparatus. The reels 22 and 24 may be mounted and the reel 24 driven in any suitable and appropriate manner. Such mounting and driving means are well known in the various arts that deal with the treating and handling of strands and it is not believed necessary for the understanding of this invention to describe or show them in detail here.

The strand 23 passes from the reel 22 up along the outside of the housing 20 and over a guide sheave 25 also outside of the housing. Thence it passes through an appropriate small aperture in the housing (not shown) behind the sheave 25 and over another guide sheave 26 within the housing. Thence the strand passes over and once or more around a capstan 27, from which it passes down and under a pair of multiply grooved sheaves 29 located below the surface of the coating material contained in the bottom portion of the housing which is formed as a tank to hold a suitable supply of the liquid coating material. From the second guide sheave or roller 29 the strand 23 passes upward between the first of a gang of convex wiper die rollers 31 and the corresponding one of a gang of matched concave wiper die rollers 32. Thence the strand passes on to and again around the capstan 27 and thence to and over one of the sheaves of a multiple

sheave 35. From the sheave 35 the strand passes in succession over a number of similar multiple sheaves 36, 37, 38, 39 and 40 and back around capstan. Thence the strand passes down and again under the submerging guide sheaves 29 in the liquid supply tank and thence upwardly between the second pair of wiper die rollers 31 and 32. The strand then passes over and around the capstan, over the second sheave 10 of the multiple sheave 35, and thence again over the guide sheaves 36, 37, 38 and 40 and to the capstan. It is carried again down into the bath, through the wiper dies, around the capstan, and through the tortuous drying path as many times 15 as found to be necessary to produce the desired thickness of coating material on the strand. On the last pass, the strand passes between an independent pair of wiper die rollers 42 and 43. When this object is attained the strand passes 20 from the capstan over the last sheave of the multiple sheave 39 to a guide sheave 46 and out through a suitable aperture in the housing to an external guide sheave 47 from which it passes down outside of the housing to be wound up on 25 the take-up reel 24.

The structure and operation of the multiple sheaves 35, 36, 37, 38, 39 and 40 and of the capstan 27 are no part of the present invention but are described in detail and claimed in co-pending applications Serial Nos. 228,353 and 228,354, filed by the same inventors on the same date as this application.

The particular subject of the present invention is the construction and mode of operation of the wiper dies more particularly disclosed in detail in Figs. 2, 3, 4 and 5. Turning now to Fig. 3 first, the rear wall of the housing 20 is formed to the left of its center with a pair of vertical slots within which are secured two vertically grooved guide members 48 and 49. A vertically disposed plate-like base member 50 is formed and dimensioned to slide in the slots of the members 48 and 49. Near the top of the base member 50 is a horizontal forwardly extending integral table 51, to the under-side of which, at its right hand edge and near the front and back edges, are secured two rightwardly and downwardly curved arms 52 and 53. In these arms, at their lower ends, is journalled a shaft 54 upon which are rigidly mounted the several concave wiper die members 32, 33, 43 to be driven in rotation by the shaft 54. At the forward end of the shaft 54 there is secured a gear 55 which is driven by suitable gearing from a motor 56. On top of the table 51 there is mounted a handle 57 by means of which the table 51 and the base member 50 may be drawn upwardly and removed from the tank together with the concave dies 32 and 43. A latch 58 may also be mounted on the table 51 if desired to lock the member 50 and therewith the whole assembly in operating position to prevent it from being moved out of place by the tension of the strands passing over the sheaves 29, the sheaves 29 being also preferably mounted on members 59 mounted on or integral with the table 51.

In the right hand portion of the rear wall of the housing 20 a second vertical plate-like supporting member 60 is rigidly mounted. A horizontal arm 61 integral with the member 60 extends out nearly across the tank from the base member 60. On the left hand face of the arm 61 are secured two guide members 62 and 63 presenting vertical channels into which fit a vertical removable plate 64. The plate 64 is formed

with a horizontal arm 65 extending out to the left and bifurcated at its extremity. The outer ends of the bifurcations are formed with journals 66 and 67 for horizontal shaft 68. A horizontal plate-like member 69 has at its forward and rear extremities depending arms 70 and 71 pivotally secured on the shaft 68 and extending below the shaft 68 and there provided with journals 72 and 73 to receive a rotatable shaft 74 upon which are rigidly secured the convex wiper die rollers 10 31. A separate narrow horizontal plate 76 located in front of the plate 69 is also pivoted on the shaft 68 and carries in its lower portion a stub shaft upon which the wiper die roller 42 is rigidly secured. The removable base member 64 15 may be conveniently formed on its upper edge with a handle for lifting the member 64 and the assembly carried by it when it is desired to move the wiper die rollers 42 and 31 from the bath. To the under-side of the plate 69 is secured one end 20 of a tension spring 75, the other end of which is attached to a lug 77 formed on the lower part of the member 64. Similarly a tension spring 78 is attached at its upper end to the under-side 25 of the right hand part of the member 76 and to a lug 79 similar to the lug 77. The springs 75 and 78 tend to draw the right hand parts of the members 69 and 76 downwardly and thus press the convex wiper die rollers 42 and 31 respectively and independently against the corresponding rigidly positioned die rollers 43 and 32. The gear 55, which is driven from the motor 56 and which drives the shaft 54 also meshes with a gear 80 rigidly mounted on the shaft which supports the die roller 42 and thus drives this roller. At 35 the rear end of the shaft 54 is a gear 81 rigidly secured to the shaft 54 and meshing with a gear 82 rigidly secured on the shaft 74 and thus serving to drive the convex die rollers 31. A member 83 is pivotally mounted on the arm 61 so that the 40 left hand end will extend over a portion of the upper edge of the member 64 when this is in operating position to hold the member immovably in place. A pin 85 in one end of the latch serves 45 for manual manipulation of the latch while a spring 86 tends to hold the latch in the locked position.

A circular cam 87 is pivotally secured in the aperture 88 of the arm 61 to lie under the extended right hand extremities of the members 50 69 and 76 and is operated by means of a lever 89 attached thereto. The cam 87 is a simple circular wedge so formed that when the lever 89 is in the position shown in full lines in Fig. 3, the right hand extensions of the members 69 and 76 are 55 over the thin part of the wedge and so are free to move downwardly under the tension of springs 75 and 78 to keep the convex die rollers pressed against the concave die rollers; but when the lever 89 is turned to the position shown in dotted 60 lines in Fig. 3, the right hand extremities of the members 69 and 76 are lifted and held up by the thick part of the wedge-like cam, thus retracting the convex rollers 42 and 31 from contact with the concave rollers 43 and 32 and locking the 65 convex rollers in the retracted position when it is desired to remove the member 64 and its assembly from the bath.

The handle 89 when in this latter position (dotted in Fig. 3) extends forward, and is so proportioned that it then prevents the door 103 from being closed.

Textile covered copper wire such as is used in the electrical arts will have at regular intervals along its length irregularities of over-all diam- 75

eter which may be due to enlargements caused by splices in the wire under the textile covering or to knotted threads in the covering or other causes. When such enlargements pass between any of 5 the wiper dies 31 and its corresponding wiper die 32 coming up from the bath 30, the die 31 can yield by pivoting about the shaft 68 against the spring 75 to allow the enlargement to pass between the dies. If the die 42 were on the same 10 rigid shaft with the dies 31 then each time that the dies 31 were forced away from the die 32 by an enlargement in the strand the die 42 would also back away from the die 43 and thus permit an unwiped enlargement to be formed in 15 the final coating of the wire which would not be smoothed down by subsequent passage between a pair of wiper dies. And since a splice or other knot in the strand would pass through between the dies 31 and 32 as many times as there 20 are pairs of these dies a single knot would thus produce an equivalent number of lumps on the finished coating if it were not for the independent mounting of the die 42.

While the illustrative embodiment herein disclosed is specifically disclosed for one type of strand and one type of liquid coating material the invention is not so limited but is to be thought of as limited solely by the appended claims.

What is claimed is:

30 1. In a strand treating apparatus, a housing, a shaft mounted in the housing, a plurality of wiper die rollers mounted on the shaft to be driven thereby, a base member removably secured to the housing, a second shaft having a 35 plurality of wiper die rollers mounted thereon

to coact respectively with the rollers of the first named plurality, means to mount the second shaft on the base member to be movable thereon toward and from the first shaft to bring the rollers of the second plurality into and out of contact with the corresponding rollers of the first plurality, resilient means to press the second shaft yieldingly toward the first shaft, and cam means to force the second shaft away from the first shaft when the member is to be removed 10 from the housing.

2. In a strand treating apparatus, a housing, a door in the housing, a shaft mounted in the housing, a plurality of wiper die rollers mounted on the shaft to be driven thereby, a base member 15 removably secured to the housing, a second shaft having a plurality of wiper die rollers mounted thereon to coact respectively with the rollers of the first named plurality, means to mount the second shaft on the base member to be movable 20 thereon toward and from the first shaft to bring the rollers of the second plurality into and out of contact with the corresponding rollers of the first plurality, resilient means to press the second shaft yieldingly toward the first shaft, cam means 25 to force the second shaft away from the first shaft when the member is to be removed from the housing, and a lever to actuate the cam means and formed to extend when in cam actuating position into the path of the door and thereby 30 to prevent closing of the door when the second shaft is held away from the first shaft by the cam means.

WALDEMAR C. EWALDSON.
